UNITED STATES PATENT OFFICE.

TEODORO LARREY AND LUIS GODARD, OF MEXICO CITY, MEXICO.

COMBINED STEAM SUPERHEATER AND DRAFT-DISTRIBUTING DEFLECTOR.

Application filed April 16, 1923. Serial No. 632,484.

To all whom it may concern:

Be known that we, TEODORO LARREY and LUIS GODARD, citizens of the United Mexican States, residing at Mexico City, Mexico, have invented certain new and useful Improvements in Combined Steam Superheaters and Draft-Distributing Deflectors, of which the following is a specification.

The present invention relates to combined steam superheaters and draft distributing deflectors for boilers, and is essentially an improvement on, or development of, the constructions disclosed in our prior patent, No. 1,441,360, granted January 9, 1923, and our pending application, No. 309,550, filed July 9, 1919; the precise features constituting the improvements in question being herein-after fully set forth.

The invention is specially well adapted for application to, or installation in, steam locomotives, though it is obviously not limited to that particular use; and when so used, it results in a saving of both water and fuel consumption, an increase in the life of the fire-box, tube sheets and tubes, and a reduction in the number of broken stay bolts and of boiler failures, while at the same time providing for sufficient superheating of the steam to more than offset any condensation throughout the expansion period of the steam in the cylinders. It also aims to provide greater locomotive efficiency, due to increased steam capacity of the boiler as a result of proper draft distribution and the high quality of steam delivered to the cylinders by the absorption of waste heat instead of useful heat for steam generation, as in the case of fire-tube superheaters.

The invention further resides in the provision of an extremely simple and comparatively inexpensive device of the character above described which may be readily installed in a locomotive in much less time than a fire-tube superheater, thereby greatly reducing the period during which the locomotive must remain in the shop.

With the above and other objects in view, the invention involves the particular construction and arrangement of parts herein-after described and claimed, though it is to be understood as susceptible of modifications and changes within its scope as so claimed.

In the accompanying drawings:

Figures 1 and 2 are, respectively, a front elevation and a part-sectional side elevation of one embodiment of the invention.

Figs. 3 and 4 are front elevations of one member of the combined superheater and deflector and the division plate therein, respectively.

Figs. 5 and 6 are vertical sections taken, respectively, on line 5—5, Fig. 3 and line 6—6, Fig. 4.

Figs. 7 and 8 are views, corresponding to Figs. 1 and 2, of a slightly modified form of the invention.

Figs. 9 and 10 are front elevations of one of the deflector members and its internal division plate in said modification.

Figs. 11 and 12 are vertical sections on lines 11—11 and 12—12 of Figs. 9 and 10, respectively.

Fig. 13 is an enlarged vertical sectional view of a concavo-convex deflector which may be substituted for the flat deflectors of Figs. 2 and 8.

In the above figures, the invention has been shown as applied to a locomotive boiler which, as previously stated, is its principal use; but it will be apparent that the invention may also be applied to marine and stationary boilers of various forms, as well as to other and different types of boilers and to still other uses. Hence, the precise application of the invention here illustrated has of itself no limiting action.

Referring to Figs. 1—6, 1 indicates the shell of the boiler of a locomotive of standard or conventional type, 2 the smoke-box thereof, 3 the flue tubes passing through the boiler, and 4 the front tube sheet to which the forward ends of the tubes are attached and through which they open. The smoke stack of the locomotive is indicated at 5, and the dry pipe of the boiler at 6, all of which parts are, or may be, of the usual form.

The improved superheating deflector 7 is located in the smoke-box 2 a slight distance in front of the tube sheet 4; and, as here shown, has a straight, horizontal top edge 100 and curved side and bottom edges which generally conform to the curvature of the boiler shell 1 but are spaced therefrom, while the upper corners are rounded, so that the device as a whole presents a substantially 105 heart-shaped appearance. It preferably consists of two counterpart hollow members 7^a, the mutually adjacent vertical inner edge faces of which are fastened together by pairs of alining straps or lugs 8 soldered to the front faces of said members and bolted or otherwise secured to each other as indicated

5 at 9. The two members are connected to the dry pipe 6 by individual inlet pipes 10 branching thereto, from said pipe; the delivery end of each inlet pipe having a coupling flange 11 which is bolted to a similar coupling flange 12 and to an apertured circular boss 13 formed on a division plate 14 disposed within the deflector member 7^a.

10 The division plate 14 is arranged in spaced relation to the front and rear walls of the deflector member, as shown in Fig. 5, and is held in place by means of a multitude of small stay bolts 15 carrying spacing sleeves 16. It conforms to the internal 15 shape of the deflector member, and thus divides the interior of said member into counterpart front and rear chambers or conduits, communication between which is provided by a marginal space or passage 17 at the 20 edge of the plate, interrupted at intervals by projecting centering lugs 18. The boss or shoulder 13 is located in the upper portion of the division plate and projects forwardly therefrom, as represented in Figs. 25 4 and 6, so as to abut directly against the front wall of the deflector member (Fig. 5), which latter is cut away at that point to permit the outward projection of the annular part of the coupling 12. A second circular 30 boss or shoulder 19 is formed in the lower portion of the division plate, but is imperforate instead of apertured and projects rearwardly instead of forwardly into direct abutting relation with the rear wall of the 35 deflector member; said wall and boss being dished slightly inward and interfitted. The front wall of the deflector member is cut away directly opposite the boss 19, and a coupling 20 is fastened thereto and connected 40 to a second coupling 21 on the adjacent end of an outlet pipe 22, the latter being connected to the pipe or passage 23 which 45 conducts the dry superheated steam to the engine cylinders. The joints between the various couplings are made tight to prevent escape of steam, as will be understood.

50 As in our patented construction, previously referred to, the present superheating deflector has its periphery coinciding with the peripheral tubes in the tube sheet, so that the area of the surface of the deflector confronting said tubes is substantially equal to the area of the tube zone of the tube sheet; from which it follows that the products of combustion emerging from the tubes 55 will discharge radially over the entire confronting surface of the deflector, and the draft in each tube will be substantially equal to the draft in every other tube.

60 Due to the construction and arrangement of parts as above described, the saturated steam coming from the pipe 6 will flow into and through the inlet pipes 10 and thence through the apertures in the upper bosses 65 13 on the division plates 14 directly into the

70 rear chambers or conduits of the deflector members, where it will spread out radially in all directions, forming relatively thin layers which completely fill said chambers and which will readily and quickly be superheated by the flames and hot gases of combustion coming from the flue tubes and impinging against the deflector. From the aforesaid rear chambers or conduits, the superheated steam will pass forwardly all 75 around the edges of the division plates and through the marginal passages 17 into the front chambers or conduits of the deflector members, whence it will pass outwardly through the pipes 22 and will be supplied in 80 superheated condition to the engine cylinders through the parts 23.

85 The construction illustrated in Figs. 7 to 12 differs from that previously described only in certain details; and therefore the same numerals have been used as appear in Figs. 1 to 6, wherever possible, in order to avoid unnecessary description. In the modified form, the pipe 6 is connected directly to the parts 23 which supply the 90 superheated steam to the cylinders by means of a pair of oppositely curved pipes 24; the separate inlet and outlet pipes 10 and 22 being omitted, and their places taken by small pipes 10' and 22' which lead, respectively, from the upper portions of pipes 24 to the upper parts of the deflector members 7^b, and from the lower parts of said members back to the lower portions of pipes 24. The deflector 7' is here shown as suspended 95 from the tube sheet 4 by a series of brackets 100 25 or the like, and the outer ends of the pipes 10' and 22' are fastened to couplings 12' and 20' (Figs. 9 and 11) which are 105 welded on the front face of the deflector. These couplings 12' and 20' are disposed immediately opposite the upper and lower bosses 13' and 19' formed on the division plates 14' (Figs. 10 and 12); said bosses 110 projecting laterally into direct abutting relation to the front and rear walls of the deflector members, and the upper bosses being 115 centrally apertured, as in the first form. The operation is substantially identical with that previously described and, hence, need not be repeated.

120 The further modification, represented in Fig. 13, shows a form of superheating deflector, the members 7^c which are of bowed or concavo-convex construction, but are otherwise similar to those shown in Figs. 10 to 12, the operation being likewise the same. The corresponding parts are indicated by the same reference numerals with the addition of the exponent "2," and the 125 couplings are omitted, the showing being somewhat diagrammatic.

130 We claim as our invention:—

1. A steam superheater for boilers, comprising a hollow case dividing means in 130

said case spaced from the front and rear walls thereof to form separate front and rear steam conduits or chambers, said dividing means being marginally spaced from the 5 peripheral wall of the case to provide a communication passage between the chambers thereof; piping for supplying saturated steam from the boiler to one chamber; and piping leading from the other chamber 10 to deliver the superheated steam from the case for use, both the supply piping and the delivery piping opening through the same side of the case.

2. A steam superheater for boilers, comprising a hollow case; a division plate in the case spaced from the front and rear walls thereof to form separate front and rear steam conduits or chambers, said plate 15 having its marginal edges spaced from the peripheral wall of the case to provide a communication passage between said chambers; the front wall of the case having inlet means for saturated steam and separate outlet means for superheated steam, and the division plate having means coacting with said inlet means for conducting the in-coming saturated steam immediately into the rear chamber; piping connected with the inlet means for supplying the saturated steam 20 thereto; and piping connected with the outlet means for delivering the superheated steam from the case for use.

3. In a boiler, the combination of a smoke-box; flue tubes passing through the boiler and terminating at their forward 35 ends in a tube sheet in the smoke-box; a combined steam superheater and deflector located in the smoke-box adjacent the tube sheet and having its periphery coinciding 40 with the peripheral tubes in the tube sheet, whereby the area of the surface of the deflector confronting said tubes is substantially equal to the area of the tube zone of the tube sheet so that the products of combustion discharge radially over the entire 45 confronting surface of the deflector; said deflector comprising a hollow case having within it a division plate which is spaced from the front and rear walls thereof to 50 form separate front and rear steam conduits or chambers, and which has its marginal edge spaced from the peripheral wall of the case to provide a communication passage between said chambers; piping for supplying 55 saturated steam from the boiler directly to the rear chamber to be superheated by the products of combustion impinging upon the deflector; and piping communicating with the front chamber to conduct the superheated steam therefrom for use.

4. In a boiler, the combination of a smoke-box; flue tubes passing through the boiler and terminating at their forward

ends in a tube sheet in the smoke-box; a combined steam superheater and deflector 65 located in the smoke-box adjacent the tube sheet; said deflector comprising a hollow case having within it a division plate which is spaced from the front and rear walls thereof to form separate front and rear steam conduits or chambers, and which has its marginal edge spaced from the peripheral wall 70 of the case to provide a communication passage between said chambers; piping for supplying saturated steam from the boiler 75 directly to the rear chamber to be superheated by the products of combustion impinging upon the deflector; and piping communicating with the front chamber to conduct the superheated steam therefrom for 80 use.

5. A steam superheater for boilers, comprising a hollow case; a division plate in the case spaced from the front and rear walls thereof to form separate front and 85 rear steam conduits or chambers, said chambers having a communication passage between them at the margin of the plate; an apertured boss projecting outward from the front wall of the case; a boss projecting forward from the front face of said plate into abutting engagement with the said front case wall directly opposite the first-named boss and having an aperture in registration 90 with the aperture therein; piping communicating with said bosses for supplying saturated steam therethrough from the boiler directly to the rear chamber; and piping leading from the front chamber to deliver the superheated steam from the case for use. 100

6. A steam superheater for boilers, comprising a hollow case embodying flat front and rear vertical walls disposed in spaced, parallel relation; a flat division plate in said case disposed parallel with said walls and 105 spaced therefrom to form separate front and rear vertical steam conduits or chambers, said chambers having a communication passage between them at the margin of the plate; an apertured boss projecting outward from one wall of the case; a boss projecting laterally from the division plate through one of said chambers into abutting 110 relation with the first-named boss and having an aperture in registration with the aperture therein; piping communicating with said bosses for supplying saturated steam therethrough from the boiler directly to the other chamber; and piping leading from the first-named chamber to deliver the 115 superheated steam from the case for use. 120

In testimony whereof we affix our signatures.

LUIS GODARD.
TEODORO LARREY.
